**COMBINED BASE AND MOUNTING PLATE FOR
A PHONOGRAPH OR SIMILAR ARTICLE**

Richard H. Van Den Berg, Milwaukee, Wis.

Filed Jan. 18, 1962, Ser. No. 68,367

Term of patent 3½ years

(Cl. D56—4)

FIGURE 1 is a top plan view of a combined base and mounting plate for a phonograph or similar article, showing my new design; with the mounting plate being omitted for convenience of illustration;

FIGURE 2 is a bottom plan view thereof;

FIGURE 3 is a side elevational view thereof, the side opposite being substantially the same in appearance;

FIGURE 4 is an end elevational view thereof, the end opposite being substantially the same in appearance except that the power connection recessed area is omitted;

FIGURE 5 is a top plan view with the mounting plate included;

FIGURE 6 is a top perspective view of the design as shown in FIG. 5; and

FIGURE 7 is a cross-sectional view taken on the line 7-7 of FIGURE 5.

I claim:

The ornamental design for a combined base and mounting plate for a phonograph or similar article, as shown and described.
